Attorney.

UNITED STATES PATENT OFFICE.

ARTHUR G. HUNTER, OF SHERMAN, TEXAS.

NUT AND PIPE WRENCH.

1,359,894.

Specification of Letters Patent. Patented Nov. 23, 1920.

Application filed October 14, 1919. Serial No. 330,595.

To all whom it may concern:

Be it known that I, ARTHUR G. HUNTER, a citizen of the United States, residing at Sherman, in the county of Grayson and State of Texas, have invented certain new and useful Improvements in Nut and Pipe Wrenches, of which the following is a specification.

This invention pertains to wrenches of that class adapted for use in turning nuts, and relates particularly to the provision of a wrench with a portion of the handle formed integral with the shank thereof, said portion being adapted for locking engagement with a suitably formed, detachable handle member.

In the drawings, Figure 1 is a longitudinal front edge view of the nut wrench only, constructed according to my invention. Fig. 2 is a side view of the same with the gripping-jaws attached thereto. Fig. 3 is a back view of Fig. 2.

Referring now to the drawings, it will be seen that my improved wrench comprises, essentially, a primary fixed jaw 1, a shank 2, and a secondary sliding jaw 3. The jaw 1 is formed integral with the forward terminal of the shank, while the secondary jaw 3 is mounted for sliding movement longitudinally of the shank, adapting it in practice to coöperate with the jaw 1 for operating upon a nut or the like. In the front edge of the shank 2, for a portion of its length, is provided a rack formed of a plurality of transversely disposed teeth 4, and in the front edge of the jaw 3 is a recess 5 intersected by alining elongated apertures (not shown.) In said apertures is mounted an adjusting screw 7 having threaded thereon a knurled head or disk 8, the said disk being confined within the recess 5 in the movable jaw. Integrally formed with the screw 7 is a locking member comprising a block 9, having teeth 10 on its inner face, the same being adapted to register with the teeth 4 formed on the shank 1 of the wrench. The block 9 is connected between the arms of a vertically movable yoke 11, by means of a pin 12 secured in the said yoke, and slidably through an elongated aperture 14 in the block. The upper portion of the yoke 11 acts as a finger lug, beneath which, and the forward end of the jaw 3, is mounted a coiled expansion spring 15, that serves to sustain the teeth 10 of

the block 9, in intermeshing engagement with the teeth 4 in the shank. The yoke is counter-bored at 16, and the jaw at 17, to receive the ends of the spring and provide seats therefor.

The pipe attachments embodied in my invention as shown, consist of cross-sectionally flat jaws 18 and 19, bifurcated at their rear ends to straddle the shank 2, whereby the arms 20 of the former jaw, formed by the bifurcations, are arranged in planes at either side of the shank and there securely clamped adjacent to the inner edge of the jaw 1, by a rotatable arbor 21, which bears at its ends in sockets 22 formed in the arms 20, and has a medial portion 23, enlarged diametrically and offset eccentrically to the axis thereof, said medial portion being provided with an integral lateral extension 24 for turning the arbor. Hence it will be observed that upon the arbor 21 being caused to undergo, say, a half revolution in one direction, as to the position indicated in Fig. 2, the jaw 18 will be caused to move bodily in the direction of the jaw 1 and shank 2, and be clamped thereto. A downwardly extended lip 25, of the extension 24 engages the outer face of the jaw 1 and aids in retaining the parts in adjusted position. To release the jaw 18, the arbor 21 is given a half-revolution in the opposite direction, in which position of the parts the locking device may be detached from the sockets 22 and the jaw removed.

The pipe jaw 19 embraces the shank 2 in a manner similar to that of jaw 18, and their widths are equal to that of the fixed and sliding jaws of the wrench, and their operative faces are toothed or serrated. A socket 26 is formed in each side of the movable jaw 3, in which outwardly and upwardly extending lips 27 of the jaw 19 enter, and by which it is clamped adjacent to the inner face of the jaw 3, and is additionally secured thereto by the lip 28.

The handle embodied in my invention as shown, comprises a reduced and longitudinal extension 29 of the shank 2, having a beveled portion at 30, and a transversely disposed triangular notch 31 formed in the inner surface of the extended and downwardly curved terminus thereof. 32 represents a detachable portion conforming in contour to that of the part 29, the forward end is inclined to register with the beveled

portion 30, and the extended end provided with a lip 33, carrying a triangular projection 34 engaging the notch 31, by which the extended ends of the handle parts are securely joined. The opposite end of the member 32 is secured to part 29 by a rectangular sleeve 35, and said sleeve is held in position by a set screw 36 which construction permits the assembling of the 10 movable jaw on the shank.

From the foregoing it is thought that the construction, operation, and many advantages of the herein-described invention will be apparent to those skilled in the art without further description, and it will be understood that various changes in the size, proportion, and minor details of construction may be resorted to without departing from the spirit or sacrificing any of the 15 advantages of the invention.

Having thus described my invention, what

I claim as new and desire to secure by Letters Patent, is—

In a wrench, a shank having a reduced and extended portion formed thereon comprising about one half of the handle thereof, a beveled seat at the forward end of the reduced portion, a triangular notch in the inner surface of its opposite downwardly curved end, and a detachable handle portion of similar contour, to that of the extended shank portion, beveled at one end to fit the beveled seat of the extension, the other end provided with an upwardly extended lip having a triangular projection 35 engaging the notch in the said extension, and a rectangular sleeve slidable on the shank adapted to be forced over the abutting beveled portions of the members to retain them in position.

In testimony whereof I affix my signature.

ARTHUR G. HUNTER.
